P. KOBYLANSKI

COMBINED CHAIR AND STEPLADDER

Filed July 5, 1923

INVENTOR

PETER KOBYLANSKI
BY *H G Hinings*
ATTY.

UNITED STATES PATENT OFFICE.

PETER KOBYLANSKI, OF HAMILTON, ONTARIO, CANADA.

COMBINED CHAIR AND STEPLADDER.

Application filed July 5, 1923. Serial No. 649,646.

To all whom it may concern:

Be it known that PETER KOBYLANSKI, a citizen of Ukrainia, residing at Hamilton, in the county of Wentworth and Province of Ontario, Canada, has invented certain new and useful Improvements in a Combined Chair and Stepladder, of which the following is a specification.

My invention relates to a combination chair and step-ladder, and consists essentially of a chair, the back of which is linked to the seat structure and capable of being elevated to a suitable height comparable with that of a domestic step-ladder and provided with rungs serving the combined purpose of steps and back-rest, and chair arms pivoted to the forward chair legs and to the movable back which serve as struts for the back when the latter is elevated.

The principal object of the invention is to provide means for converting a chair into a household step-ladder, so that two important household necessities are combined in one unit.

A further object is to provide a step-ladder which is combined with an ordinary article of household furniture, so that the former is always at hand when required, as it is customary with ordinary separate step-ladders to store them in some remote portion of the dwelling, such as the basement or attic.

A still further object is to provide means for the centre of gravity to fall between the forward and rear chair legs so that the weight of the person occupying the step-ladder will not overbalance the structure.

Another object is to provide means for effecting rigidity to the structure when the chair back is elevated to form the step-ladder.

Still another object is to provide a device of the class specified which will be simple, durable, efficient, and inexpensive to manufacture.

These, together with other objects may be attained by the combination, construction, and arrangement of the parts as will be hereinafter more fully described, illustrated in the accompanying drawing, and pointed out in the claim hereunto appended.

Referring to the drawing:

Figure 1 is a side elevation of the invention showing the device in chair form, in step-ladder form in dotted lines, and in stage of being converted, also in dotted lines.

Figure 2 is a perspective view showing the step-ladder form;

Figure 3 is an enlarged detailed perspective view of the back raising parts; and,

Figure 4 is an enlarged detailed perspective view of the opposite side of the device showing the back raising parts and the hinged braces for rigidly holding the back in elevated position.

Similar reference characters refer to similar parts throughout the several views.

The chair is formed of the usual front legs 2 which extend upwardly as arm supporting columns 3, rear legs 4; seat structure comprising front rail 5, rear rail 6 and lateral rails 7; and rungs 8. These members form a unit and are constructed each rigid with the other. The chair back comprises side uprights 9 connected by a plurality of horizontal rungs or steps 10 spaced at a suitable distance and comparable with the steps or rungs of an ordinary ladder. The uprights 9 are pivotally connected at their lower end parts to links 11 at 12, whose opposite ends are pivoted to the end parts of the rear rail 6 at 13.

Arms or brackets 14 are pivotally connected to the upper ends of the columns 3 at 15, and at their opposite ends are pivotally connected to the uprights 9 at 16.

The chair back comprised of the uprights 9 and rungs 10 may be elevated or lowered, as illustrated in diagram in Figure 1, by rotating the links 11 on the pivots 12, so that the latter assume an upright or depending position as the case may be. It will be noticed that the arms or brackets 14 are substantially longer than the lateral rails 7 thus effecting a rearward acclivity to the chair back comparable to that of an ordinary arm or easy chair, and that said arms are horizontal or parallel with the chair rails when the chair back is in normal position.

When the chair back is elevated, as shown in Figure 2, the arms 14 move upwardly at their rear ends and serve as brackets or struts for the support of the back which when so elevated assumes a position having a forward acclivity.

There are provided for further support of the back when it is elevated, a pair of folding arms 17 secured by hinges 18 to the top of the rear rail 6. When the structure is in normal position, as shown in Figures 1 and 3, these folding arms are in parallel

relation with rail 6, as shown in the said figures, and when the back is elevated to form a step-ladder, the folding arms 17 are swung to a vertical position, as viewed from the front or rear, and engage flanges 19 on the uprights 9, thus affording rigidity between the relative parts. When the back is elevated, the limited length of the arms effect a forward acclivity thereto, so that the centre of gravity is intermediate of the forward and rear legs of the structure. In this manner the structure is prevented from over-balancing with the weight of the person occupying it when used as a step-ladder.

15 There has thus been provided a simple and efficient device of the character described and for the purpose specified.

Having now fully described the invention, what I claim and desire to secure by Letters Patent, is;

20 In a device of the class described, a structure comprising seat rails and chair legs, and

chair arm supports forming part of the forward legs, links pivotally connected to the ends of the rear seat rail, a back structure comprising lateral uprights connected by spaced combined back supports and ladder rungs, said uprights having pivotal connection with the free ends of said links, combined chair arms and back supporting struts pivotally connected to said chair arm supports and to said lateral uprights, and folding arms hingedly secured to the top of the rear seat rail adapted to lie parallel therewith when the back structure is in normal position, and to be swung vertically to engage flanges on the said uprights when the back structure is in elevated position.

25 In testimony whereof I have affixed my signature.

PETER KOBYLANSKI.
